(57) **CLAIM**

The ornamental design for light fixture, as shown and described.

DESCRIPTION

1. Light fixture
Lighting units, especially public lighting fixtures and/or stage lighting.

1.1 is a perspective view of a light fixture according to the new design,

1.2 is a rear view thereof,

1.3 is a top view thereof,

1.4 is a side view thereof,

1.5 is a front view thereof.

The broken lines shown in the drawings illustrate portions of the article and form no part of the claimed design.
